[57] CLAIM

The ornamental design for a twist top closure, as shown and described.

DESCRIPTION

FIG. 1 is a perspective view of a twist top closure showing my new design, the same being shown in closed configuration with the upper cap portion positioned adjacent to the lower base portion;

FIG. 2 is a top plan view thereof;

FIG. 3 is a front elevation view thereof, the rear elevational being a mirror image;

FIG. 4 is a right side elevation view thereof, the left side elevation being a mirror image; and,

FIG. 5 is a perspective view thereof with the same being shown in open configuration with the upper cap portion moved to raised position with respect to the lower base portion.

The bottom and interior of the twist top closure form no part of the claimed design.
